(57) **CLAIM**

The ornamental design for a slide board, as shown and described.

DESCRIPTION

FIG. 1 is a front, right and top perspective view of a slide board, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of the area labeled 9 in FIG. 2; and,

FIG. 10 is an enlarged view of the area labeled 10 in FIG. 2.

The broken lines shown in the drawings are included for the purpose of illustrating portions of the slide board that form no part of the claimed design. The dot-dash broken lines in FIGS. 2, 9, and 10 depict the boundaries of the enlargements that form no part of the claimed design.

1 Claim, 10 Drawing Sheets
